UNITED STATES PATENT OFFICE.

ARTHUR McGONAGLE, OF EAST ORANGE, NEW JERSEY, ASSIGNOR TO STARRETT COTTON GIN COMPANY, OF NEW YORK, N. Y., A CORPORATION OF NEW YORK.

COTTON-GIN.

SPECIFICATION forming part of Letters Patent No. 759,390, dated May 10, 1904.

Application filed June 26, 1903. Serial No. 163,167. (No model.)

To all whom it may concern:

Be it known that I, ARTHUR McGONAGLE, a citizen of the United States of America, and a resident of East Orange, county of Essex, State 5 of New Jersey, have invented certain new and useful Improvements in Cotton-Gins, of which the following is a specification, reference being had to the accompanying drawings, forming a part thereof.

10 My invention relates to improvements in cotton-gins, and particularly to the form of gin known as the "roller" cotton-gin.

My invention consists in the employment of air-currents in combination with a roller and 15 stripper, as will hereinafter appear.

The object of my invention is to increase the efficiency of a cotton-gin of this type by employing air-currents to assist in drawing cotton fibers past the stripping device.

20 I will now proceed to describe a cotton-gin embodying my invention and will then point out the novel features in claims.

In the drawings, Figure 1 is a view in central vertical transverse section of a cotton-gin embodying my invention, the section being 25 taken upon the plane of the line 1 1 of Fig. 2. Fig. 2 is a top view of same with portions thereof broken away.

For the sake of clearness and intelligibility, 30 I have illustrated herein a cotton-gin in its simplest form, parts unnecessary for a complete understanding of my invention being either omitted or shown conventionally, so as not to obscure the more essential features 35 thereof.

A roller *a* is provided, suitably mounted in bearings supported by a frame *b* and has a plurality of spirally-disposed projections or ribs *c*. These projections or ribs may conveniently 40 be formed of walrus hide or other leather and are preferably disposed around the cylinder in such a manner as to form a plurality of spiral grooves *d* of a size sufficient to receive cotton fibers, but not sufficient to permit the 45 passage therethrough of seeds and the like.

The roller *a* is arranged with its lower portion within a casing *e* and with its upper portion within a hopper *f*. At the front of said

roller a stripper *g* separates the casing from the hopper and coacts with the periphery of 50 the roller for the purpose of ginning the cotton, while at the rear of the said roller the casing converges toward a point *h* in close proximity to the periphery of the roller, for a purpose presently to be described. 55

A seed-board *i* of any suitable construction may conveniently form one wall of the seed-hopper and terminates in proximity to the stripper.

In carrying out my invention I provide 60 means for creating a draft and so causing air-currents to pass between the face of the stripper and the periphery of the roller into and through the casing *e*, and for this purpose have shown herein a fan-blower or suction apparatus *j*, connected on its inlet side with the lower end of the said casing. At its discharge side the said fan-blower may connect with any desired point of delivery, such as the baling-presses commonly employed in baling cotton. 70

In operation cotton is supplied to the hopper *f* and rests against the seed-board, the stripper, and the periphery of the ginning-roller. The ginning-roller is then revolved in the direction of the arrow, Fig. 1, and the 75 fan-blower is simultaneously operated to create a suction within the casing *e*. The combined action of the air-currents with the stripper and the ginning-roller will cause the cotton fibers to be carried rapidly into the 80 casing and to very largely increase the efficiency of a gin of this character over the ordinary form of roller-gin in which pneumatic pressure is not employed. The cotton fibers will be carried rapidly into the casing, 85

while the seeds will be held back by the stripper and will fall against the seed-board, to be discharged in any suitable manner. No mechanism is herein shown for operating the seed-board, as the same forms no part of my present invention. Air-currents will not only be drawn into the casing between the stripper and the ginning-roller, but will also be drawn into the casing between the contracted portion *h* thereof and the periphery of the ginning-roller upon the side opposite to that at 90 95

which the stripper is disposed. The effect of the currents of air passing the point *h* will be to strip from the roller the fibers of cotton, which are received in the spiral grooves 5 *d* and have a tendency to be carried completely round by the roller in its revolution. The point *h* being in quite close proximity to the periphery of the roller the currents of air will be drawn into the casing through the 10 grooves *d*, and this will tend to very thoroughly clean and strip the roller of fibers. The cotton fibers received into the casing will be carried down into the suction apparatus and delivered thereby at the discharge side 15 thereof to any desired point.

What I claim is—

1. In a cotton-gin, the combination with a roller and a stripper adapted to coöperate with the periphery thereof in a ginning operation, 20 of means for causing the air-pressure on one side of the point of coaction of the said stripper with the said roller to be less than that on the other side.
2. In a cotton-gin, the combination with a 25 roller and a stripper adapted to coöperate with the periphery thereof in a ginning operation, of means for disturbing the equilibrium of air-pressure at the point of coaction of the said stripper with the said roller.
3. In a cotton-gin, the combination with a 30 roller and a stripper coacting therewith, of means for causing air-currents to pass between the periphery of the roller and the stripper.
4. In a cotton-gin, the combination with a 35 roller and a stripper coöperating therewith, of means for drawing air between the periphery of the roller and the stripper.
5. In a cotton-gin, the combination with a 40 roller and a casing partially inclosing same, of a stripper forming a closure for the casing at one side of the said roller, and arranged with its edge in close proximity to the said roller, and means for causing air-currents to 45 pass between the edge of the stripper and the periphery of the roller into the casing.
6. In a cotton-gin, the combination with a grooved roller and a casing partially inclosing same, of a stripper forming a closure for the 50 casing at one side of the said roller, and arranged with its edge in close proximity to the said roller, and means for setting air-currents in motion between the edge of the stripper and the periphery of the roller into the casing.
7. In a cotton-gin, the combination with a 55 spirally-grooved roller and a casing partially inclosing same, of a stripper forming a closure for the casing at one side of the said roller, and arranged with its edge in close proximity to the 60 said roller, and means for setting air-currents in motion between the edge of the stripper and the periphery of the roller into the casing.
8. In a cotton-gin, the combination with a

roller and a casing partially inclosing same, of 65 a stripper forming a closure for the casing at one side of the said roller, and arranged with its edge in close proximity to the said roller, and suction apparatus connected with the said casing.

9. In a cotton-gin, the combination with a grooved roller and a casing partially inclosing same, of a stripper forming a closure for the casing at one side of the said roller, and arranged with its edge in close proximity to the 75 said roller, and suction apparatus connected with the said casing.

10. In a cotton-gin, the combination with a spirally-grooved roller and a casing partially inclosing same, of a stripper forming a closure for the casing at one side of the said roller, and arranged with its edge in close proximity to the 80 said roller, and suction apparatus connected with the said casing.

11. In a cotton-gin, the combination with a 85 casing and a roller arranged partially within and partially without the said casing, of suction apparatus connected to the said casing.

12. In a cotton-gin, the combination with a 90 casing and a grooved roller arranged partially within and partially without the said casing, of suction apparatus connected to the said casing.

13. In a cotton-gin, the combination with a 95 casing and a spirally-grooved roller arranged partially within and partially without the said casing, of suction apparatus connected to the said casing.

14. In a cotton-gin, the combination with a 100 casing and a hopper, of a ginning-roller arranged partially within the casing and partially within the hopper, a stripper at one side of the said roller between the said hopper and the said casing, and means for causing air-currents to flow from the hopper past the stripper to within the casing.

15. In a cotton-gin, the combination with a 105 casing and a hopper, of a ginning-roller arranged partially within the casing and partially within the hopper, a stripper at one side 110 of the said roller between the said hopper and the said casing, and a suction apparatus connected with the said casing.

16. In a cotton-gin, the combination with a 115 casing *e*, and a ginning-roller *a* arranged with a portion thereof within the said casing, the said casing having a portion thereof, as *h*, in close proximity to the periphery of the roller on one side thereof, and provided with a stripper *g*, in proximity to the roller, on the opposite side thereof, of a suction apparatus connected to the said casing, substantially as set forth.

ARTHUR McGONAGLE.
